[57] CLAIM

The ornamental design for a plastic paint container, as shown and described.

DESCRIPTION

FIG. 1 is a side elevational view of a plastic paint container showing our new design with the lid removed; FIG. 2 is an elevational view of the right side of FIG. 1, the left side being identical thereto;

FIG. 3 is a top plan view of the plastic paint container with the lid attached;

FIG. 4 is a bottom plan view thereof; and

FIG. 5 is a top plan view with the lid removed;

FIG. 6 is an enlarged scale fragmentary cross-sectional view taken along line 6—6 of FIG. 3.

FIG.1

FIG.2

FIG. 3
